UNITED STATES PATENT OFFICE

VINCENT J. BURRY, OF BERWYN, ILLINOIS, ASSIGNOR TO WOODMAN RAILWAY SUPPLY COMPANY, OF CHICAGO, ILLINOIS, A CORPORATION OF ILLINOIS

JOURNAL BOX

Application filed August 8, 1927. Serial No. 211,361.

This invention relates to journal boxes and particularly to hinged lids therefor.

The object of the invention is to provide a novel and improved means for fastening the lid to the box.

Another object is to provide a journal box lid which can be readily and quickly attached to the box without employing the use of a number of tools.

Another object is to provide fastening means which can be readily applied and replaced by ordinary trainmen and which will securely hold the lid in position.

Another object is to provide a journal box which has a greater sealing area than the ordinary boxes.

The accompanying drawings illustrate a preferred embodiment of the invention and the views therein are as follows:

Fig. 1 is a front view of a journal box lid fastened to the journal box parts being broken for the sake of clearness.

Fig. 2 is a sectional view taken on the line 2—2 of Fig. 1.

Fig. 3 is a perspective view of the fastening bolt or rivet.

Referring to the drawings 1 designates a standard A. R. A. journal box to which the lid 2 is swingingly attached by means of a bolt or rivet 3.

A double spiral spring 4 has a loop 5 between the two spirals 6, 6 and has two free ends 7, 7 as shown. The two free ends are adapted to fit in holes 8 provided for this purpose in the lugs 9 formed integral with the lid.

The journal box has a projection 10 integral therewith which is curved on the inner side as at 11 to accommodate the fastening member 3 which also passes through the perforated lugs 11'. The outer edge of the projection has a flat beveled face 12, Fig. 2, to provide a projection or cam 13 against which the spring 4 bears to cause tension on the spring for maintaining the lid in closed

position. A metal guard or clip 13' is fixed to the inner side of the spring to prevent wear on the spring when the lid is being opened or closed.

The fastening member 3 is provided with 50 a slot 14 and a recess 15 at one end as clearly shown in Fig. 3 and is adapted to be received in the perforated lugs 11' of the journal box, and in the perforated ears 16 of the lid. The opening 17 in the lid is enlarged and is adapted to receive the sprung end 18 of the member 3 as shown in Fig. 1.

When the fastening member 3 is inserted in the holes in the journal box and lid the member 3 is backed up at its head 19 in any suitable manner and the slotted end 20 of the fastening member is pounded, as with an ordinary hammer. This pounding or pressure exerted on the slotted end 20 causes the parts 21 and 22 of the member 3 to spring 55 out and conform with the shape of the enlarged opening 17 as shown in Fig. 1.

By providing fastening means of this character only the minimum amount of tools are required and the operation of inserting the 60 fastening member in place is simple. Heretofore, the lids were fastened to the box in many ways such as by using a rivet which had a head on each end; one head being formed after the rivet was inserted.

Another means employed was by providing a rivet which had a split end and extended beyond the end of the box, the ends being bent over in a manner similar to the way one would bend the ends of an ordinary cotter pin. These methods required the use of additional tools and many times the metal in the rivet would break and fracture causing the box to rattle or perhaps the lid would fall off and be lost.

In the present invention the bolt can be very economically made and the method of fastening the lid to the box is easy and simple and it can be done by the most unskilled labor. The invention is particularly advan-

75

tageous on the road where trainmen may make the repairs or replacements, requiring but the minimum time and using only a hammer. The head may be backed up in any 5 convenient manner such as by using a coupling pin or by using a rock picked up from the roadbed.

I have also designed the box so that it is almost completely sealed, to prevent foreign 10 matter from entering therein. The flange 23 on the box extends all around the box except at a small place on the top where it must be left off to provide the necessary clearance for the spring. On the ordinary lid a flange 15 just extends around the bottom and sides and in some instances the ordinary lid may have the flange extend to the points 24, 24, Fig. 1. By extending the flange inward as at 25, 25 the chances of dirt and other matter entering 20 the box is greatly reduced.

While my invention pertains primarily to standard A. R. A. journal boxes it is to be understood that it may be applied successfully to other journal boxes and to all other 25 devices where this type of fastening means may be employed. The invention shows a fastening member provided with a head on one end but I may provide a member having both ends split and held in position in the 30 same manner as I have described above relative to the one end.

Changes may be made in the form, construction and arrangement of parts without departing from the spirit of the invention or 35 sacrificing any of the advantages thereof and I reserve the right to make all such changes as fairly fall within the scope of the following claims.

I claim:

- 40 1. A journal box provided with a lid having perforations to receive a fastening member, one of said perforations having an interior rounded enlargement, and a fastening member having a split end expanded into 45 conformance with the contour of said enlargement.
- 45 2. A journal box having a perforated lid, one of said perforations being interiorly enlarged, and a fastening member engaging 50 said perforation and having one end thereof split, the split end of said member being sprung intermediate its ends, to conform with the contour of said enlargement for fastening the lid to the box.
- 55 3. A journal box including perforated lugs, a lid for said box having perforations therein, and a fastening member for connecting said lid to said box extended through 60 said perforated lugs and said perforations having a split extending inwardly from one end including an enlarged portion disposed in and expanded to conform with an interior enlargement in one of said perforations to retain the fastening member in position.
- 65 4. A journal box including perforated

70 lugs, a lid for said box having perforations therein, a fastening member for connecting said lid to said box extended through said perforated lugs and said perforations having a split extending inwardly from one end including an enlarged portion disposed in and expanded to conform with an interior enlargement in one of said perforations to retain the fastening member in position, and 75 spring means for retaining said lid in closing position.
